(21) Appl. No.: **29/884,468**

(57) **CLAIM**

(22) Filed: **Feb. 12, 2023**

What is claimed is the ornamental design for an offset optic mount for a firearm, as shown and described.

DESCRIPTION

Related U.S. Application Data

(63) Continuation-in-part of application No. 17/506,606, filed on Oct. 20, 2021, now abandoned.

FIG. 1 is an elevated rear right side perspective view of an offset optic mount for a firearm showing Applicant's new design.

(51) **LOC (14) Cl.** **22-01**

FIG. 2 is an elevated rear left side perspective view of the optic mount of FIG. 1.

(52) **U.S. Cl.**

FIG. 3 is a depressed rear left side view of the optic mount of FIG. 1.

USPC **D22/110**

FIG. 4 is a depressed rear right side view of the optic mount of FIG. 1.

CPC **F41G 11/003** (2013.01)

FIG. 5 is a top plan view of the optic mount of FIG. 1.

(58) **Field of Classification Search**

FIG. 6 is a rear elevational view of the optic mount of FIG. 1, the front side being a mirror image thereof.

USPC D22/108–110; D21/573

FIG. 7 is a left side elevational view of the optic mount of FIG. 1.

See application file for complete search history.
